UNITED STATES PATENT OFFICE.

TRUE M. AVERY, OF GLENS FALLS, NEW YORK, ASSIGNOR TO THE UNION BAG & PAPER COMPANY, A CORPORATION OF NEW JERSEY.

MECHANISM FOR CONTROLLING THE RUNNING OF A WEB OF PRINTED MATERIAL.

1,256,286.

Specification of Letters Patent. Patented Feb. 12, 1918.

Application filed June 9, 1915. Serial No. 33,009.

To all whom it may concern:

Be it known that I, TRUE M. AVERY, a citizen of the United States, residing at Glens Falls, New York, have invented certain new and useful Improvements in Mechanism for Controlling the Running of a Web of Printed Material, of which the following is a clear, full, and exact description.

10 This invention relates to mechanism for controlling the running of a web of printed material such as wall paper, paper for paper bag, etc. It is customary to print advertisements which are to appear on paper bags 15 on a web of paper before the bags are made up in a paper bag machine, and it is desirable to obtain a register or control of the web in its passage through such paper bag machine, which operates on it at points or 20 intervals which have first been designated or fixed when it is run through the first machine. It is also desirable in cutting out wall paper borders and designs to run a web of paper on which the border or design 25 is printed through a machine or mechanism in which a registry of the cutters with the borders or designs can be obtained. It is also desirable to obtain such a registry in a second printing press while the latter is to 30 impose an imprint upon a web which has already been printed in another machine. The present invention has the above and other objects in view such as the electric control, through the medium of a specially 35 prepared web, of the means whereby such registrations are obtained.

These being among the objects of the present invention, the same consists of certain features of construction and combinations of parts to be hereinafter described 40 and then claimed with reference to the accompanying drawings illustrating desirable embodiments of the invention, in which—

Figure 1 is a side elevation of one embodiment of the invention in which it is shown as applied to mechanism provided with draw-rolls which are timed from the web of printed material so as to obtain the desired registry;

50 Fig. 2 is a plan of the same mechanism;

Fig. 3 is an enlarged detail of a portion of the electric control device;

Fig. 4 is an enlarged sectional detail, partly in plan, of clutch mechanism such 55 as shown in Figs. 1 and 2;

Fig. 5 is an enlarged sectional view of the differential gearing shown in Figs. 1 and 2;

Fig. 6 is a section on the line 6—6 Fig. 5;

Fig. 7 is a side elevation of a modification of the clutch mechanism and differential gearing;

Fig. 8 is a plan of another form of gearing;

Fig. 9 is a side view of the parts shown in Figs. 8 and 10; and

Fig. 10 is a section on the line 10—10, Fig. 9.

In carrying out the present invention, the web of paper or other material is preferably perforated along its margin simultaneously with the printing of the paper in the printing press. The web 11 is clearly shown in Fig. 2 as provided with linear perforations 12 extending along one of its margins, the perforations being equidistantly spaced apart, so that the said perforations can establish an accurate control of the second machine or mechanism through which the web is run, substantially as shown in Figs. 1 and 2. Preferably the perforated web of paper is taken from the first machine in the form of a roll 13, shown in Fig. 1, the shaft of which is mounted in a suitable frame 14. In said figure the web is assumed to travel from left to right and in its travel it first passes preferably over an idler 15, and before it passes over a second idler 16 it passes over an electrical control device or other suitable control device which is located in a plane somewhat above that of said idlers.

The electrical control device mentioned is shown in Figs. 1 and 2, and a part thereof is shown in Fig. 3. Briefly, this device comprises a guide-roll 17 for the web, upon which roll there is located at one end a loose collar or metallic ring 18, which is provided with a series of pins or teeth 19 which are equidistantly spaced around said ring for a distance corresponding with the distance between two adjacent perforations on the perforated web. The said ring is adapted to slip or turn slightly in one or the other direction with respect to the roll 17. During this relative movement, a lug 20 on said ring is adapted to strike one or the other of two insulated electrical contacts 21, 22. A battery 23 supplies current, and one side of the battery may be grounded upon the frame 14, while the other side of said battery is connected by means of wires 24, 25, with electro-

magnets 26, 27, from which wires 28, 29, respectively lead to brushes 30, 31, which are mounted on and insulated from the frame 14. Said brushes bear upon corresponding 5 rings of a commutator 32 which is mounted upon the shaft of the roll 17, while said rings are respectively electrically connected with the contacts 21, 22. When contact is made between the lug 20 and one of said 10 contacts 21, 22, the current passes to that side of the battery which is grounded on the frame of the machine. It will be seen that if from any cause the speed of the perforated web deviates from the peripheral speed 15 of the roller 17, which is timed to the speed of the machine or mechanism which operates on the web the loose ring 18 will shift relatively to said roller. If the speed of the web is greater than roller 17, the lug 20 will be 20 brought against contact 21, thus completing a circuit which will energize the magnet corresponding with said contact 21. If the speed of the web becomes less than roller 17, the lug 20 will make electrical contact with 25 the contact 22 and thus complete a circuit which will energize the other magnet. As the web does not hug the roll 17 very tightly, it will slip one way or the other without much friction.

30 The function of the electromagnets 26, 27, will now be described. Magnet 26 may conveniently be termed the "slow-down" magnet, and magnet 27 the "speed-up" magnet, and said magnets are adapted to control 35 suitable clutch mechanism. Referring to Figs. 1, 2 and 4, one form of clutch mechanism comprises a shaft 33 which is constantly driven from a suitable source of power and is provided with a bevel gear 34 40 which meshes with a bevel gear 35 upon a shaft 36. This shaft is preferably arranged in vertical position and is mounted upon the frame 14. Upon this shaft there are located friction cones 37, 38, which have a key and 45 groove connection therewith so that they will not only be continuously turned in one direction by said shaft but are slidable upon said shaft. Friction cone 38 is adapted to coöperate with friction cone 40 which is 50 mounted loosely upon the shaft 36 in a fixed location, and the cone 40 is provided with a hub on which is located a bevel gear 41, which meshes with a bevel gear 42 located upon a shaft 43 which is suitably mounted 55 on the frame 14. Friction cone 37 is adapted to coöperate with a friction cone 44 also mounted upon shaft 36 and carrying a bevel-gear 45 which is also in mesh with bevel-gear 42 at a point diametrically opposite 60 bevel-gear 41. From this construction and arrangement it will be clear that when the friction cones 38, 40, are in engagement, the shaft 43 will be turned in one direction and that when the cones 37 and 44 are in engagement, said shaft 43 will be turned in oppo-

site direction. The coöperating pairs of cones are caused to engage at different times by the energization of the magnets 26 and 27, one of which is energized when its corresponding insulated contact is engaged by 70 the lug 20 on the roll 17. To this end the armatures of said magnets are pivotally connected with levers 46, 47, respectively, which are pivoted to the frame 14 and 46^a and 47^a, and are provided with forks which engage 75 with grooved hubs of the friction cones 37, 38. When one or the other of the levers 46, 47, is operated by its magnet, it causes the engagement of the concomitant cones, and this engagement lasts only as long as it takes 80 to shift the perforated web of paper to proper position, such shifting automatically breaking the circuit through the lug 20 so that the magnet is deenergized, at which time a spring 50 connecting the actuating 85 levers 46, 47, retracts the shiftable cone of the pair of cones which were in engagement at the time. When this action is taking place, one of the pinions 41, 45, rotates the bevel-gear 42 in a direction corresponding 90 therewith, which direction of rotation has been selected by the appropriate magnet.

Shaft 43 before mentioned, is provided with a worm 51 which turns with the shaft in one or the other direction according to 95 which of the magnets has been energized. Referring more particularly to Fig. 5, it will be seen that the worm 51 is in mesh with a worm-wheel 52 which is mounted loosely upon a shaft 53. The said worm-wheel 52 is ordinarily at rest and when at rest it means that the perforated web is traveling at proper speed. This worm-wheel 52 forms a part of a differential gear which will be described later, but before doing so, it should be stated that the shaft 53 is constantly driven and carries a draw-roll 54, which coöperates with a draw-roll 55 intended to draw the web of printed or similar material at the proper rate of speed. 100 Said draw-rolls may be assumed to be the draw-rolls of a paper bag machine, with which is usually associated means for forming the paper into a tube. Such forming means is, however, omitted herein. Under 105 the present invention it is desired to cause the proper registry of the imprint on the web of paper with a cutting device 93, which may be a pair of cutter rolls as shown, or substitute cutting means, such as is well 110 known in paper bag machines. Said cutting device is timed to operate at the same speed as roll 17, for which purpose it may be operated through an intermediate train of gears, comprising gears 94, 95, as shown in 115 Fig. 2. If the cutting device 93 is substituted by a printing roll, a proper registration of the imprint caused by said printing roll will be obtained with the matter already printed on said web. On the other 120

hand, the said cutting device may be substituted by a cutter roll such as used in wall paper cutting machines, which cutter under the present invention is timed to a predetermined speed of the web of material so that borders and designs will be brought substantially in register with the cutters. Frequently the shaft 53 which is timed under the present invention, will cause the roll thereon to travel at a peripheral speed which is different from the predetermined speed for the web of material. Sometimes the web will slow down and at other times will speed up, but in order to obtain the proper registration, means such as under the present invention are provided, said means preferably comprising the differential gearing above referred to.

In addition to the worm-wheel 52 before mentioned, the differential gearing comprises a gear 56 mounted loosely upon the shaft 53 and having external spur teeth 57 and internal spur teeth 58. One of the pinions of a pair of constantly driven pinions 59 meshes with the external teeth 57 as shown in Figs. 1 and 2, said pinions being connected by the intermediate gears 94 before mentioned, with a gear-wheel 60 located on one end of the roll 17. On one side of the worm-wheel 52 there is fastened on a stud 62 an intermediate pinion 63 which is in mesh with the internal spur teeth 58 of gear 56, and diametrically opposite said point of engagement said intermediate pinion 63 is in mesh with a gear 64 keyed to shaft 53. It is clear that the constantly driven loose gear 56 imparts its motion through its internal teeth 58 and the intermediate pinion 63 to the keyed-on gear 64 of shaft 53, thereby rotating the draw-roll on said shaft. Worm-wheel 52 is ordinarily locked against rotation while said gears drive the shaft 53 constantly. But when the web of printed material begins to creep or get out of register, with the cutting or printing rolls, it is retarded or accelerated by the turning of the worm 51 and worm-wheel 52 produced by the action of the previously described detecting and controlling means comprising the electromagnets. When the worm-wheel 52 is turned, the intermediate pinion 63 is moved through a circular path in one or the other direction as is obvious.

A modification of the clutch mechanism is shown in Fig. 7, in which electromagnets 26^a and 27^a corresponding with magnets 26, 27, are employed. A miter gear 65 mounted in a suitable frame 66 meshes with a miter gear 67 which is located on a shaft 68, which is driven continuously by the miter gear 65. At right angles to the shaft 68 there is a shaft 69 which is adapted to be rotated at intervals, whenever the web of paper is out of registry, to which end

shaft 68 carries a bevel-gear 70 which is in mesh with pinions 71, 72 on said shaft 69. Pinions 71, 72, are loose upon shaft 69 and respectively carry friction cones 73, 74, which are respectively associated with co-operating cones 75, 76, having a tongue and groove connection with shaft 69, and therefore adapted to rotate shaft 69 whenever coacting cones 74, 76, or 73, 75, are brought into engagement. Such engagement is effected by the magnets 26^a, 27^a, acting through levers 77, 78. At the center of the shaft 69 is a worm 79, which engages worm-wheel 80, mounted on draw-roll shaft 81. The differential gear controlled by said worm-wheel is indicated in dotted lines only, and the details of its construction may be the same as that previously described. This modification of the invention differs from the one previously described in that the connection is more direct and the friction cones 75, 76, which are directly actuated by the electromagnets, except when in frictional engagement with cones 73, 74, respectively, and which drive the shaft 69, remain stationary. Furthermore, the friction cones 73, 74, revolve continuously in contra-distinction to the reverse in the modification before described.

A modification of the differential gear is shown in Figs. 8, 9 and 10. In this modification a gear 83 turns loosely upon a draw-roll shaft 84 and one face thereof is provided with a bevel-gear 85 with which meshes a bevel pinion 86 which also meshes with a bevel-gear 87 keyed to said shaft 84. Ordinarily the driven gear 83 drives the shaft 84 at a continuous rate of speed, at which time the pinion 86 is locked in one position with respect to the shaft 84. In order, however, to time the speed of the web with respect to the predetermined speed of the cutters 93 or printing device, said pinion 86 is so mounted that its axis can be shifted around the shaft 84. To this end the pinion-shaft 88 is mounted in a radial direction in the worm-wheel 89, said pinion turning within an opening 90 at one side of said worm-wheel. When the worm 91 turns the worm-wheel 89, the axis 88 of pinion 86 is displaced with reference to shaft 84 in one or the other direction, depending upon which of the electromagnets has been energized, thereby obtaining a difference in the rate of speed of the shaft 84 and hence the draw-roll. Any suitable clutch mechanism can be employed in connection with this modification of the differential gear.

Other modifications can of course be made as parts may be omitted, added and substituted without departing from the spirit and scope of the invention as expressed in the claims.

What I claim as new is:—

1. In mechanism for controlling the run-

- ning of a web of printed material, the combination of means for drawing a linearly perforated web from a supply of such material, means for operating on said web, to 5 produce for example an imprint, relatively to the imprint on said web, a timing device controlled by said web and comprising a shiftable, toothed, timing member, the teeth of which engage constantly with the perforations of said web, independent separately operable devices controlled one at a time by said timing device according to 10 whether the latter runs faster or slower than the predetermined speed of said operating means, and means controlled by said separately operable devices one at a time for timing the speed of said drawing means and producing a registration of the imprint on said web with said operating means.
- 20 2. In mechanism for controlling the running of a web of printed material, the combination of means for drawing a web from a supply of such material, means for operating on said web relatively to the imprint thereon, speed detecting means controlled by said web, and comprising a rotary member in constant positive engagement with said web to travel at the speed of the engaged web portion and independent separately operable devices controlled one at a time by said rotary member, according to 25 the speed of said member, and means controlled by the similar operation of either of said devices for timing the speed of said drawing means and producing a registration of the imprint on said web with said operating means.
- 30 3. In mechanism for controlling the running of a web of printed material, the combination of means for drawing a web from a supply of such material, means for operating on said web relatively to the imprint thereon, electrical speed detecting means controlled by said web, and comprising independent separately operable magnets of 35 similar function, and means controlled by the similar operation of either of said magnets for timing the speed of said drawing means and producing a registration of the imprint on said web with said operating means.
- 40 4. In mechanism for controlling the running of a web of printed material, the combination of means for drawing a web from a supply of such material, means for operating on said web relatively to the imprint thereon, electrical speed detecting means controlled by said web, and comprising an accelerating magnet and a separate retarding magnet, and means controlled by said magnets and timing the speed of said drawing means and producing a registration of the imprint on said web with said operating means.
- 45 5. In mechanism for controlling the running of a web of printed material, the combination of means for drawing a web from a supply of such material, means for operating on said web relatively to the imprint thereon, a pair of constantly driven clutch members, a pair of companion clutch members to coöperate therewith, means for detecting the speed at which said web is running and for automatically throwing the clutch members of one pair of clutches alternately into coöperative relation with the clutch members of the other pair, and means controlled by one of said pairs for in turn

ning of a web of printed material, the combination of means for drawing a web from a supply of such material, a guide roller for said web, impression means for operating on said web relatively to an imprint thereon, automatic timing means associated with said guide roller and with which said web is in constant positive engagement so as to be controlled at all times by the speed of said web, and differential gearing automatically controlled from said timing means in a plurality of rotated positions of said roller, and connected up with said drawing means for timing the speed of said drawing means in any one of said positions of said guide roller and in accordance with a predetermined speed of said web.

6. In mechanism for controlling the running of a web of printed material, the combination of a pair of draw rolls, each running at the same peripheral speed as the other, a guide roller for said web, impression means for operating on said web relatively to an imprint thereon, automatic timing means associated with said guide roller and with which said web is in constant positive engagement so as to be controlled at all times by the speed of said web, and differential gearing automatically controlled from said timing means in a plurality of rotated positions of said roller, and connected up with said draw rolls for timing the speed of said draw rolls in any one of said positions of said guide roller and in accordance with a predetermined speed of said web.

7. In mechanism for controlling the running of a web of printed material, the combination of means for drawing a web from a supply of such material, timing means with which said web is in constant positive engagement so as to be controlled at all times by the speed of said web, clutch mechanism controlled by said timing means and comprising constantly driven members and movable members engageable with aforesaid members at different times, and differential gearing controlled from said clutch mechanism for timing the speed of said drawing means relatively to a predetermined speed of said web.

8. In mechanism for controlling the running of a web of printed material, the combination of means for drawing a web from a supply of such material, means for operating on said web relatively to the imprint thereon, a pair of constantly driven clutch members, a pair of companion clutch members to coöperate therewith, means for detecting the speed at which said web is running and for automatically throwing the clutch members of one pair of clutches alternately into coöperative relation with the clutch members of the other pair, and means controlled by one of said pairs for in turn

timing the speed of said drawing means and producing a registration of the imprint on said web with said operating means.

9. In mechanism for controlling the running of a web of printed material, the combination of means for drawing a web from a supply of such material, means for operating on said web relatively to the imprint thereon, a pair of constantly driven clutch members, a pair of companion clutch members to coöperate therewith, means for detecting the speed at which said web is running and for automatically throwing the clutch members of one pair of clutches alternately into coöperative relation with the clutch members of the other pair, a worm-shaft intermittently operable by said clutches, and means controlled by said worm-shaft for in turn timing the speed of said drawing means and producing a registration of the imprint on said web with said operating means.

10. In mechanism for controlling the running of a web of printed material, the combination of means for drawing a web from a supply of such material, means for operating on said web relatively to the imprint thereon, differential gearing for operating said drawing means, a pair of constantly driven clutch members, a pair of companion clutch members to coöperate therewith, means for detecting the speed at which said web is running and for automatically throwing the clutch members of one pair of clutches alternately into coöperative relation with the clutch members of the other pair, and means controlled by one of said pairs for in turn timing the speed of said differ-

ential gearing and producing a registration of the imprint on said web with said operating means.

11. In mechanism of the class described, the combination of a driving member, a driven member, differential gearing connecting said members, and comprising a worm-wheel for timing said differential and said driven member, a worm meshing with said worm-wheel, clutch mechanism to act on the latter, comprising constantly driven members and members adapted to coöperate with said constantly driven members, and means for automatically and alternately selecting coöoperating pairs of said clutch members so as to intermittently turn said worm in one or the other direction.

12. In mechanism of the class described, the combination of a driving member, a driven member, differential gearing connecting said members, and comprising a worm-wheel for timing said differential and said driven member, a worm meshing with said worm-wheel, clutch mechanism to act on the latter, comprising constantly driven members and members adapted to coöperate with said constantly driven members, and electro-magnetic means for automatically and alternately selecting coöoperating pairs of said clutch members so as to intermittently turn said worm in one or the other direction.

Signed at Hudson Falls, N. Y., this 3 day of June 1915.

TRUE M. AVERY.
